UNITED STATES PATENT OFFICE.

FRANK KUHN, OF DETROIT, MICHIGAN.

ELECTRICALLY-HEATED HOT-PLATE.

1,107,321.

Specification of Letters Patent. Patented Aug. 18, 1914.

Application filed September 8, 1913. Serial No. 788,715.

To all whom it may concern:

Be it known that I, FRANK KUHN, a citizen of the United States of America, residing at Detroit, in the county of Wayne and State of Michigan, have invented certain new and useful Improvements in Electrically-Heated Hot-Plates, of which the following is a specification, reference being had therein to the accompanying drawings.

- 10 The invention relates to electric heaters of the type known as hot plates in which the heating unit is arranged adjacent to a flat heat-distributing body mounted upon a supporting stand.
- 15 The invention comprises various features of construction, by which the manufacture is simplified and cheapened and improved results are obtained in operation, as herein-after set forth.
- 20 In the drawings: Figure 1 is a perspective view of the several sections inclosing the heater detached; Fig. 2 is a vertical cross section through the assembled structure; Fig. 3 is a detail sectional view showing the 25 manner of attaching the legs to the stand.

To increase the efficiency of the hot plate and also to reduce the downward radiation of heat to the minimum, it is desirable to interpose a dead-air space between the heating unit and the supporting stand. This decreases the loss of heat by reason of the poor heat-conducting property of a static gas; but to form such a dead-air space there must be continuous retaining walls which will conduct down a certain amount of heat to the supporting stand. With my improved construction I form the dead-air space by a hollow member, preferably formed of cast metal having an annular wall marginally 30 bearing against the hot plate. To prevent the downward radiation of heat conducted through this wall, I have provided the bottom of the hollow member with downwardly-projecting lugs, preferably integral 35 therewith. These lugs are supported upon a stand forming a baffle or radiation shield, and the space between the hollow member and the stand is surrounded by a perforated case, producing a finished appearance to the 40 structure, and at the same time permitting of a free air circulation, so that the downwardly conducted heat is dissipated by convection.

In detail, A is the hot plate, to the lower 45 side of which the heating unit B is clamped, with a clamping and heat-distributing plate

C therebeneath, threaded studs D and nuts E being preferably the clamping means.

F is the hollow member, preferably a casting, and having an annular outer wall upon 50 which the margin of the hot plate is seated. This member is also provided with integral lugs G depending therefrom and its bottom plate H is cut away at H' for the terminal connection, as hereinafter described.

I is a flat plate or shield, which forms the top of the stand, having depending legs J secured thereto. These legs are arranged opposite the lugs G on the member F and are secured to said lugs by suitable means, 65 such as screws. The plate I is preferably formed of sheet metal, while the legs may be formed of castings, thereby simplifying and cheapening the construction. On the bottom of the plate I is secured a terminal 70 contact box K, from which conductors lead through insulator bushings L placed in apertures in the plate I. There is also a switch M mounted beneath the plate I so as to be operable from the front of the stand, and the 75 insulator block M', upon which this switch is mounted, extends through an aperture in the plate I and above the same a sufficient distance to hold the conductors out of contact with the metal parts. The conductors 80 N from the terminals pass from the bushings L to the block M' where they are coupled to the switch, while a plurality of conductors O lead from the switch to the hot plate. These conductors O pass through the 85 space between the member F and the plate I, and are secured to an insulator block P, which latter is clamped to the hot plate and projects downward through the cutaway portion H' into the space in which the conductors O are located. Extension conductors Q formed of strips of sheet metal are 90 electrically connected to the conductors O and are clamped to the block P by screws Q'. These extension conductors are bent at right 95 angles and extend into the grooves in the block P to points in proximity to the hot plate, so that the resistor wire may be connected thereto without exposing any considerable length to the air, and thereby preventing overheating or burning out of the resistor at this point.

The parts being constructed as described, in assembling, the hot plate and heating unit are first clamped together by the studs 100 D and nuts E, the insulator block B being also secured in position. The plate is then

placed upon the member F, being marginally seated thereon and with the insulator block P extending through the cut-away portion H'. Connection is then made to the conductors O which are flexible and of sufficient length to permit of turning back the members A and F so as to engage the clamping screws Q'. The perforated ring R is then placed to surround the lugs G and to form 10 a downward continuation of the annular wall of the member F. This will permit the free circulation of air between the member F and the plate I, but at the same time the naked conductor wires are inclosed so 15 as to prevent any danger of short circuit.

All of the parts are secured together by the studs D, some of which pass through the bottom plate I and are clamped thereto by nuts E.

20 What I claim as my invention is:

1. An electric heater, comprising a hot plate, an electrical heating element clamped to the underside of said plate, an insulator block secured to said hot plate and depending therefrom, terminal connections for the resistor mounted on said insulator block, a hollow member having an annular outer wall forming a seat for said hot plate and a bottom cut away at one point for the passage of said insulator block, supporting lugs depending from said hollow member, a stand comprising legs and a top plate on which latter the lugs of said hollow member are supported, terminal contacts and a controlling switch mounted on said stand beneath the same, and electrical connections between said terminal contacts and switch and between the latter and the terminals on said insulator block, being detachably secured to the latter.

2. An electric heater, comprising a hot plate, an electrical heating unit clamped to the underside of said plate, a stand for supporting said plate, having terminal connections mounted thereon, a hollow cast member interposed between said hot plate and stand, comprising an annular wall, a bot-

tom and depending lugs, said lugs being supported on said stand, and a perforated annular casing surrounding said lugs enclosing the space between said hollow member and stand.

3. An electric heater, comprising a hot plate, an electrical heating unit clamped to the underside thereof, a stand having a top plate and depending legs, electrical connections mounted upon said stand, and a hollow member interposed between said stand and said hot plate formed of cast metal having an annular wall forming a seat for the hot plate, a bottom plate and depending lugs, the latter registering with the legs of said stand and being secured thereto.

4. An electric heater, comprising a hot plate, an electrical heating unit clamped to the underside of said plate, a stand comprising a top plate and depending legs, electrical terminal connections mounted on said stand on the underside thereof and provided with upwardly-extending insulators passing through apertures in said top plate, a hollow member interposed between said stand and hot plate comprising an annular wall forming a seat for the hot plate, a bottom, and depending lugs, an insulator block on said hot plate depending therefrom and passing through an aperture in the bottom of said hollow member, terminal connections for the heating unit mounted on said insular block, naked conductors for connecting said terminal connections on said block with the terminals mounted on said stand, and a perforated shield surrounding the space between said stand and hollow member in which said naked conductors are located and permitting the free circulation of air.

In testimony whereof I affix my signature in presence of two witnesses.

FRANK KUHN.
